(57) **CLAIM**

The ornamental design for a display screen with display screen or portion thereof with graphical user interface, as shown and described.

DESCRIPTION

The patent or application file contains at least one drawing executed in color. Copies of this patent or patent application with color drawings will be provided by the Office upon and request and payment of the necessary fee.

FIG. 1 is a front view of a display screen or portion thereof with graphical user interface, showing a first embodiment of the new design;

FIG. 2 is a second embodiment thereof;

FIG. 3 is a third embodiment thereof; and,

FIG. 4 is a fourth embodiment thereof.

The outermost dash-dot broken line rectangle showing the display screen and all other even broken lines showing portions of the graphical user interface are included for the purpose of illustrating portions of the article and form no part of the claimed design.

1 Claim, 4 Drawing Sheets
